(57) **CLAIM**

The ornamental design for a dual vial holder, as shown and described.

DESCRIPTION

FIG. 1 is a front-top-right perspective view of a dual vial holder showing our new design;

FIG. 2 is a front view of the dual vial holder of FIG. 1;
FIG. 3 is a rear view of the dual vial holder of FIG. 1;
FIG. 4 is a right side view of the dual vial holder of FIG. 1;
FIG. 5 is a left side view of the dual vial holder of FIG. 1;
FIG. 6 is a top view of the dual vial holder of FIG. 1; and,
FIG. 7 is a bottom view of the dual vial holder of FIG. 1.
The portions of the dual vial holder shown in broken lines
form no part of the claimed design.
